(57) **CLAIM**

The ornamental design for the fiberglass spraying apparatus, as shown and described.

DESCRIPTION

FIG. 1 is a front isometric view of the fiberglass spraying apparatus showing our new design;

FIG. 2 is a front view thereof;

FIG. 3 is a bottom view thereof;

FIG. 4 is a right side view thereof;

FIG. 5 is a left side view thereof;

FIG. 6 is a top view thereof; and,

FIG. 7 is a rear view thereof.

1 Claim, 7 Drawing Sheets

FIG. 1

FIG. 2

FIG. 3

FIG. 4

FIG. 5

FIG. 6

FIG. 7
